RESTING DEVICE

Filed Aug. 18, 1928

UNITED STATES PATENT OFFICE.

FRANCES M. DAVENPORT, OF COMPTON, CALIFORNIA.

RESTING DEVICE.

Application filed August 18, 1928. Serial No. 300,474.

My invention relates to and has for a purpose the provision of a resting device characterized by the simplicity and durability of its construction and its capability of comfortably supporting the head or other portion of a person's body, so that in any instance in which a person is required to maintain substantially one and the same position for a period of time, such as, for example, in beauty parlors wherein a person receiving a permanent hair wave is required to maintain, for a period of time, a predetermined seated position with a multiplicity of heavy electrodes attached to the hair, the head of the person can be comfortably supported in a restful position, thus entirely eliminating the fatigue and discomfort usually associated with this operation.

It is a further purpose of my invention to provide a resting device of the above described character which is capable of being secured in a predetermined position to a support with the utmost ease and dispatch, and is capable of being readily adjusted to accommodate portions of the body of different dimensions.

I will describe only one form of resting device embodying my invention, and will then point out the novel features thereof in claims.

30 In the accompanying drawing

Fig. 1 is a view showing in plan one form of resting device embodying my invention, applied to a support;

Fig. 2 is a view in side elevation of the resting device embodied in Fig. 1; and

Fig. 3 is a sectional view taken on the line 3—3 of Fig. 2 and looking in the direction of the arrows.

Referring specifically to the drawing in which similar reference characters designate similar parts in each of the several views, my invention in its present embodiment comprises a pair of arms A and A' constructed of strap metal of rectangular cross section, the arms being relatively movable, and to this end the arm A' is pivotally connected at one extremity to the arm A by means of a headed pin 10 extending through plates 11 and 12 secured by rivets 13 to the arm A. The free

provide yoke sections 14 and 15 respectively, which co-operate to provide a yoke Y of substantially semi-circular contour, in which the head or neck or other portion of a person's body is adapted to be received and supported. 55 The yoke sections 14 and 15 are covered with an inner layer of electrical insulation 16 such as rubber, an intermediate layer of padding or cushioning material 17 such as felt, and an outer wear resisting layer 18 preferably of leather, to the end that the yoke will provide a comfortable cushioned support. 60

The pivotal connection of the arm A' to the arm A provides for relative adjustment of the arms to vary the size of the opening of the yoke Y so as to comfortably accommodate in the yoke, portions of persons' bodies of different dimensions, and in the present instance, the arm A' is normally urged outwardly from the arm A by means of a spring 19 so as to normally tend to increase the size of the yoke opening. The spring 19 is formed from a length of flat spring metal bent upon itself intermediate its ends to provide a pair of spring members, and is interposed between 75 the arms A and A' with the connected end of the spring members projecting between the plates 11 and 12, and the free end of one of the members provided with an angularly disposed lip 20 seating in a socket 21 formed in 80 the inner side of the arm A', to the end that displacement of the spring will be prevented.

The arms A and A' are capable of being manually adjusted inwardly of each other to decrease the size of the yoke opening, and retained in a selected position of adjustment, by means of an adjusting screw 22 threadedly mounted in a bracket 23 of U form, having parallel portions 24 secured at their free extremities to the arm A by a rivet 25, and slidably receiving the arm A', the adjusting screw 22 bearing against the outer side of the latter arm so that rotation of the screw in one direction will force the arm A' inwardly against the action of the spring 19, while rotation of 90 the screw in the opposite direction will permit the arm A' to be forced outwardly by the spring. 95

The resting device as above described is adapted to be secured to a support such as, 100

for example, the standard 26 of a permanent hair waving machine (not shown) to rigidly support the device at the proper height for the reception of the neck of a person in the 5 yoke Y while the person is seated in a chair in advance of the standard 26. To this end, the arm A is extended to provide a clamping element 27, while a second clamping element 28 is pivoted at one extremity between the 10 plates 11 and 12 by means of a headed pin 29. The clamping elements 27 and 28 co-operate to provide a clamp adapted to embrace the standard 26, and to maintain the elements in embracing relation to the standard and yet 15 permit vertical adjustment of the device on the standard to accommodate persons of different heights, a threaded stud 30 is pivoted at 31 on the free extremity of the clamping element 27 and is adapted to be freely received in a bifurcation 32 formed in the free 20 extremity of the clamping element 28. A wing nut 33 is threaded on the stud and bears against the clamping element 28 so that the clamping elements can be clamped to or released from the standard by rotating the nut 25 in one direction or the other.

From the foregoing description it will be manifest that with the resting device clamped to the standard 26 at the proper height to receive in the yoke Y the neck of a person seated immediately in advance of the standard, the head of the person will be comfortably supported by, and can be rested in the yoke, so that the fatigue and discomfort usually associated with permanent hair waving operations as a result of the necessity of maintaining attached to the person's hair for a period of time, a multiplicity of heavy electrodes, will be entirely eliminated.

Although I have herein shown and described only one form of resting device embodying my invention, it is to be understood that various changes and modifications may be made therein without departing from the spirit of the invention and the spirit and scope of the appended claims.

I claim:

1. A device of the character described comprising a pair of arms having portions co-operating to provide a yoke, means by which the arms can be secured to a support for the resting of the head or neck of a person in the yoke, the arms being adjustable relative to each other to vary the size of the yoke opening so as to accommodate heads or necks of different sizes in the yoke, means for normally urging the arms outwardly from each other to increase the yoke opening, a bracket secured to one of the arms, and an adjusting screw threaded in the bracket and engaging the other arm, for adjusting the arms inwardly of each other to decrease the yoke opening and for retaining the arms in a selected position of adjustment against the action of said urging means.

2. A device of the character described comprising a pair of arms having portions co-operating to provide a yoke, means by which the arms can be secured to a support for the resting of the head or neck of a person in the yoke, the arms being adjustable relative to each other to vary the size of the yoke opening so as to accommodate heads or necks of different sizes in the yoke, means for normally urging the arms outwardly from each other to increase the yoke opening, and means for adjusting the arms inwardly of each other to decrease the yoke opening and for retaining the arms in a selected position of adjustment against the action of said urging means comprising a U shaped bracket having parallel portions secured to one of the arms and slidably receiving the other arm, and an adjusting screw threaded in the bracket and engaging the other arm.

3. A device of the character described comprising an arm having a yoke section on one extremity thereof, a second arm having a yoke section on the free extremity thereof co-operating with the yoke section of the first arm to provide a yoke in which the head or neck of a person is adapted to rest, means for pivotally mounting the second arm on the first arm, said pivotal mounting of the second arm permitting adjustment of the latter relative to the first arm to vary the yoke opening, means for retaining the second arm in a selected position of adjustment, and means for securing the arms to a support comprising a clamping element on the first arm, a second clamping element pivoted on the first arm and co-operating with the first clamping element to provide a clamp adapted to grip the support, and means for securing the clamping elements in gripping relation to the support.

4. A device of the character described comprising an arm having a padded yoke section on one extremity thereof, plates secured to the arm, a second arm having a padded yoke section co-operating with the yoke section of the first arm to provide a yoke in which the head or neck of a person is adapted to rest, means for pivotally mounting the second arm between the plates, the pivotal mounting of the second arm permitting adjustment thereof relative to the first arm to vary the size of the yoke opening, means for retaining the second arm in a selected position of adjustment, and means by which the first arm is adapted to be secured to a support.

5. A device of the character described comprising an arm having a padded yoke section on one extremity thereof, plates secured to the arm, a second arm having a padded yoke section co-operating with the yoke section of the first arm to provide a yoke in which the head or neck of a person is adapted to rest, means for pivotally mounting the second arm between the plates, the pivotal mounting of the second arm permitting adjustment thereof

relative to the first arm to vary the size of the yoke opening, means for retaining the second arm in a selected position of adjustment, and means by which the device is adapted to
5 be secured to a support comprising an extension on the first arm constituting a clamping element, a second clamping element pivoted between said plates and co-operating with the first clamping element, and means for securing
10 the clamping elements in clamping relation to the support.

6. A device of the character embodied in claim 5 wherein said means for retaining the second arm in a selected position of adjustment comprises a spring interposed between the arms and normally urging the second arm outwardly from the first arm to increase the size of the yoke opening, and a U shaped bracket having parallel portions secured to
15 the first arm and slidably receiving the second arm, and an adjusting screw threadedly mounted in the bracket and engaging the second arm to oppose the action of the spring.

Signed at Los Angeles, in the county of Los
25 Angeles, and State of California this 4th day
of August, A. D. 1928.

FRANCES M. DAVENPORT.
